Attorney.

UNITED STATES PATENT OFFICE.

JOHN HORWOOD, OF HOXTON, LONDON, ENGLAND.

DRAWING-COMPASSES.

1,391,187.

Specification of Letters Patent. Patented Sept. 20, 1921.

Application filed March 15, 1920. Serial No. 366,010.

To all whom it may concern:

Be it known that I, JOHN HORWOOD, a subject of the King of Great Britain, residing at 10 Ivy Yard, Ivy street, Hoxton, in the county of London, in England, have invented a new and useful Improvement in Drawing-Compasses, of which the following is a specification.

The invention relates to improvements in drawing-compasses of the spring bow type.

In the accompanying drawings, Figure 1, is a side elevation of the pencil spring bow compass; Fig. 2, is a front elevation of the compass; Fig. 3, is a side elevation of the compass showing the point; Fig. 4, is the inside elevation of the spring pencil leg, and Fig. 5, is the inside elevation of the spring point.

My invention is constructed with a circular block *c* and handle *d*, the said block *c* having a spring *a* bent to the required shape and fixed thereto. The spring *a* is provided with ends *t*, and *r*, bent at right angles. These said ends *t* are perforated to receive the pencil tube *h*, and at *r* to receive the needle point *o*. On each side of the spring *a* I fix a block *h*, and to the said spring *a* I rivet an outer spring *b* with the end *s* bent at right angles to receive the upper part of the pencil tube, which is movable by means of the spring clip *m* operated in the slot *l*, and to the other or opposite side of the spring *a* I fix a spring *e* having a bow end *n*. To this end *n* and the end of the spring *a* I place an adjusting screw *p*, and nut *q*,

for the adjustment of the needle point *o*. The spring *a*, and the springs *b*, and *e*, are fixed together by rivets *j*. The blocks *h* are drilled and tapped to receive the ends of the adjusting screw *f* operated by the nut *g*, the said screw *f* being provided with a right and left hand thread, parts of the blocks *h* are provided with recesses *i* slightly cut away, through which the ends of the screw *f* project. A slot *u* is provided in the needle point end of the spring *a* through which the adjusting screw *p* passes.

The same arrangement as above described applies to either a pen bow or needle point compasses.

I claim:

Spring-bow compasses comprising a handle, a bow spring fixedly secured at its center to said handle, the legs of the bow-spring being arcuate and having perforated projections at their ends, one of said legs having secured thereto a member having a perforated projection spaced from the projection at the end of the leg, said leg being provided between said projections with a tapered slot, a spring clip slidable in said slot and adapted to hold a marker receivable in the perforations of said projections, the other leg being similarly slotted, means for adjustably securing a needle point in the perforation of said other leg, and means for adjusting the legs of said bow spring relatively to each other.

JOHN HORWOOD.
